(57) **CLAIM**

The ornamental design for an ultraviolet light sterilizer, as shown and described.

DESCRIPTION

FIG. 1 is a perspective view of the ultraviolet light sterilizer showing my new design;

FIG. 2 is a front elevational view thereof, the rear view being a mirror image thereof;

FIG. 3 is a left side elevational view thereof, the right side view being a mirror image thereof;

FIG. 4 is a top view thereof; and,

FIG. 5 is a bottom view thereof.

The broken line showing is for environmental purposes only and forms no part of the claimed design.
